UNITED STATES PATENT OFFICE

2,416,659

FRAME CONSTRUCTION

Morris H. Wolf, Cleveland, Ohio

Application October 19, 1944, Serial No. 559,416

4 Claims. (Cl. 189—36)

1

This invention relates to frames and particularly to collapsible or knock-down frames suitable for use, when assembled, for panes of window glass, wire screen, pictures or flat decorations.

The primary object of this invention is to provide a knock-down frame of the type stated that is easy and economical to ship or transport individually or in large quantities, and which will nevertheless, when assembled, stay securely and rigidly locked, like a frame that is permanently joined.

A further object is to provide a frame, the members and sections of which are easily separated for the insertion of or the replacement of a pane of glass, a sheet of wire mesh or other flat object, picture, mirror, or flat decoration.

Another object is to provide an article of this type that is economical to manufacture and use, which requires no tools or apparatus of any kind for assembly, and only a simple small prying tool for disassembly and which may be so used by persons of ordinary skill or ability.

These and other objects of the invention will be discerned from a reading of the following description and claims, together with the accompanying drawings, in which like reference characters refer to and indicate like parts, and wherein:

Figure 1 is an elevational view of a corner of a frame made in accordance with this invention and showing a part of a panel inserted therein;

Figure 2 is a front elevational view of a corner of the frame with a portion thereof removed;

Figure 3 is a rear elevational view of a corner of the frame with a portion thereof removed;

Figure 4 is a plan view of a corner of the frame assembled;

Figure 5 is a side view of a corner of the frame assembled; and

Figure 6 is an exploded view of the various parts of the frame.

This invention primarily consists of parallel pairs of border members which are assembled and arranged to form a rectangular frame. The novel feature of this invention lies in the means and method of connecting the border members together at the frame corners, and since each of the corners are substantially the same, for the purpose of simplicity only one corner will be described and claimed.

Each vertical or first border member consists of an outer strip portion and an inner strip portion, indicated and referred to by the reference characters 11 and 21 respectively. Each

2

horizontal or second border member consists of an outer strip portion and an inner strip portion which are respectively referred to and indicated by the reference characters 31 and 41. Each of these portions will be described in detail hereinafter and in the order just set forth.

The first and outer strip portion of the vertical border member consists of a grooved piece of metal, somewhat U shaped, and which has a flat flange extending along one side thereof and in planar alignment with the base of the U shaped groove. In the Figure 6 of the drawing, the strip portion 11 shows the first wall 13 of the groove 12 as being aligned with the outer edge of the strip of metal. The second wall 13a of the groove is parallel with the first wall 13 but spaced from the other longitudinal edge of the strip of metal. The two inside facing walls 13 and 13a are provided with longitudinal recesses 14 which will receive the hereinafter described beads 24.

The inner wall 13a is broken near its outer end and the small portion of the wall 13a adjacent to the end of the strip is referred to and indicated as an ear 15. When the frame is assembled the ear 15 passes through the slot 35 and fits into the notch 45 of the other related portions.

The inner strip portion of the first or vertical border member, indicated by the reference character 21, is also a flat piece of metal but has a rectangular bar integral therewith instead of a groove. This bar is referred to and indicated as a rib 22. It runs along the outer edge of the strip portion 21. The rib 22 is made to fit the groove 12 and it has longitudinal beads 24 thereon which fit into and tightly engage the aforesaid recesses 14. The inner and outer strip portions snap together and lock in the assembled position. They may, however, be pried apart with a screw driver, knife or similar tool. The end of the rib 22 is slightly short of the end of the strip 21 and the open portion of the strip 21 there is referred to as the tab 25. This cut away or eroded portion or tab 25 at the end of the strip 21 receives the end of the inner strip portion 41 of the adjacent horizontal member.

The outer strip portion 31 of the horizontal member is substantially the same as the heretofore described strip 11. Its engaging end is different, however. This strip has a corresponding groove 32 formed by the two parallel walls 33 and 33a respectively, and which runs along the outer edge of the strip. The groove 32 also has

longitudinal recesses 34 therein which receive the bead 44 hereinafter described.

The grooved portion 32 extends slightly beyond the end of the strip 31, and the groove 32 has at its extended end a small slot 35, as is clearly shown in the Figure 6 of the drawing. This slot 35 receives the heretofore mentioned ear 15 and when the strips 11 and 31 are fitted together, the groove 32 ends or abuts the outer wall 13, and the wall 33a passes through the break in the wall 13a. The wide planar surfaces of these portions are face to face and are substantially on the same plane.

The inner strip portion 41 of the second or horizontal member is made out of the same bar stock as the strip portion 21. It also has a longitudinal rib 42. Its rib also has beads 44 which engage or fit into the recesses 34 in the portion 31. It differs from the former portion in that its rib 42 extends slightly beyond the end of the strip. When assembled with the portion 21, the extended portion of the rib 42 lies over the tab 25 and the bases or planar surfaces are face to face and substantially on the same plane.

The assembled members 11-21 and 31-41 are brought together at a right angle and when the portions are snapped together at their respective beads and recesses 24-14 and 44-34, and when the ear 15 is projected through the slot 35 and into the notch 45, the frame is complete. When the portions 11 and 21 and 31 and 41 are assembled, they form at their facing flanges or wider parts, channels 52 which receive and firmly retain a glass panel 53 or a wire screen, a picture or any other flat panel. The panel or glass pane 53 must, of course, be placed and positioned before the outer portions 11 and 31 are closed with the inner portions 21 and 41.

In order to provide a more secure assembly and one which will resist vibration which might otherwise loosen the inner and outer strip portions, each member is drilled and tapped for a small screw 51. This is clearly shown in the Figure 3 of the drawing. One such screw 51 between the ends of each border member passing through the base of the grooves in the two outer strip portions and engaging the ribs 22 and 42 is sufficient to hold the frame together for all practical purposes.

At this point, it should be noted that a disassembled frame consisting of eight strip portions, four of which are grooved and four of which are ribbed, and a few simple screws, may be nested and fitted together into a relatively small package for easy and economical transportation.

While the invention has been disclosed in its preferred form, it is to be understood that the embodiment thereof as specifically set forth is suggestive only and is not to be considered in a limiting sense. Since many changes may be made in the arrangement of the particular elements shown and described and since other uses may be found for the invention than those specifically set forth, it should also be under-

stood that those changes and modifications also should be considered as being within the scope of the appended claims. Therefore, without limiting myself to the precise structure illustrated or to the specific use set forth and described, I claim:

1. In a frame, a first border member consisting of an outer strip portion having a longitudinal groove therein and an ear on the end thereof, and an inner strip portion having a longitudinal rib thereon and a tab on the end thereof; and a second border member consisting of an outer strip portion having a longitudinal groove therein and a slot at the end thereof, and an inner strip portion having a longitudinal rib thereon and a notch at the end thereof; the said inner strip portions being receivable by the outer strip portions and the said ear engaging the said slot and the said notch.
2. In a frame, a first border member consisting of an outer strip portion having a longitudinal groove therein and an ear on the end thereof, and an inner strip portion having a longitudinal rib thereon and a tab on the end thereof; a second border member consisting of an outer strip portion having a longitudinal groove therein and a slot at the end thereof, and an inner strip portion having a longitudinal rib thereon and a notch at the end thereof; the said inner strip portions being receivable by the outer strip portions and the said ear engaging the said slot and the said notch, each pair of the said outer and inner strip portions forming a lateral channel; and a means adjacent to the said ends for locking the respective portions together.
3. In a frame, a first border member consisting of a grooved portion having ears on the ends thereof and a ribbed portion having tabs on the ends thereof, and a second border member consisting of a grooved portion having slots in the ends thereof and a ribbed portion having notches in the ends thereof, the said ribbed portions being receivable by the respective grooved portions and the said ears being engaged by the said slots and the said notches, and a means on the said members intermediate the ends of the said portions fastening the portions together.
4. A frame device of the type defined in claim 3 and further characterized by the said grooved portions having recesses therein and the said ribbed portions having beads thereon receivable by the said recesses.

MORRIS H. WOLF.
